UNITED STATES PATENT OFFICE.

WILLIAM E. SWETT, OF SAN FRANCISCO, CALIFORNIA.

BOTTLE-LOCK.

SPECIFICATION forming part of Letters Patent No. 712,444, dated October 28, 1902.

Application filed May 12, 1902. Serial No. 106,908. (No model.)

To all whom it may concern:

Be it known that I, WILLIAM E. SWETT, a citizen of the United States, residing in the city and county of San Francisco, State of California, have invented an Improvement in Bottle-Locks; and I hereby declare the following to be a full, clear, and exact description of the same.

My invention relates to a device for securely locking bottles after they have been filled to prevent tampering with the contents.

It consists in forming the bottle with a frangible chambered lug cast upon one side, having a spring-pressed bolt located in the chamber, and in the formation of a stopper with a corresponding chamber or slot into which the bolt is forced when the stopper is in place, whereby the removal of the stopper can only be accomplished by breaking the frangible lug to release the bolt.

My invention also comprises details of construction which will be more fully explained by reference to the accompanying drawings, in which—

25 Figure 1 is a side elevation of the upper part of the bottle-neck, showing my improvement. Fig. 2 is a vertical section of the same. Fig. 3 is a horizontal section taken through the bolt and chamber. Fig. 4 is a view showing the extension 8.

Great difficulty is experienced in preventing the surreptitious opening of bottles and substituting inferior goods for those more valuable.

35 It is the object of my invention to protect bottles when once filled and closed from such operations.

The bottle-neck A is here shown as formed with a lug 2, projecting from one side, and 40 this lug has a chamber made horizontally into it adapted to receive a spring-pressed bolt 3. As here shown, the bolt is short and has a spiral spring attached to its rear end, as at 4, so that the two cannot be separated. The 45 stopper 5 of the bottle may also be made of glass, having a flattened portion upon one side, as at 5^a, which coincides with the inner face of the lug 2 when the stopper is inserted. A hole is made in this part 5, which when the 50 stopper is in place coincides with the hole in the lug, and as soon as the stopper has been pushed into its seat the spring will press the

bolt into this hole, and thus lock the two together. The part of the stopper which enters the bottle is preferably made of glass and of 55 sufficiently smaller diameter than the bottle-neck to allow of a surrounding portion of cork or other sufficiently-yielding material 6 to form a tight joint with the inside of the bottle-neck. The projecting lug 2 is formed 60 with a groove or channel around it, as at 7, and a curved line of connection extends from the bottom of this lug and merges into the side of the bottle-neck, as shown at 8. This connection may have a monogram or other 65 mark formed upon it when the bottle is blown or made, and it remains intact until such time as it is desired to remove the contents of the bottle. It is then only necessary to strike the outer end of the lug 2 a light blow, when 70 by reason of the groove or channel 7 it will be broken off, thus allowing the spring-bolt to be removed, and the cork can then be taken out from the bottle at will. The breaking off of this portion of the lug also destroys the 75 part 8 containing the monogram or mark, and it will then be impossible to deceive by the reuse of the bottle.

Having thus described my invention, what I claim, and desire to secure by Letters Patent, is—

1. An improved bottle having a chambered lug formed integrally therewith and projecting above and to one side of the bottle-neck, a spring-pressed bolt fitting said chamber and 85 inwardly propelled, a stopper having a corresponding chamber made in the side and adapted to register with the chamber of the bottle when the stopper is inserted and the bottle closed. 90

2. An improved bottle having a horizontally-chambered frangible lug formed upon one side thereof projecting upward above the mouth of the bottle, a stopper having a corresponding chamber substantially midway of 95 its ends and adapted to register with the chamber in the lug, a spring-pressed bolt retractable away from the stopper and into the chamber of the lug, said bolt being forced forward toward the stopper to engage the chamber of the stopper when the bottle is closed by the insertion of the latter. 100

3. An improved bottle having a horizontally-chambered lug closed at the outer end

and projecting above and to one side of the mouth end of the bottle-neck, and having a frangible circumferential line, a stopper having a corresponding chamber substantially midway of its ends and adapted to register with that of the lug when the stopper is in place and the bottle closed, a spring-pressed inwardly-impelled bolt contained within the chamber of the lug adapted to engage that of

10 the stopper.

4. The combination in a bottle of a frangible horizontally-chambered lug projecting above the bottle-neck, closed at the outer end, said lug having a stamp or imprinted connec-

tion with the bottle-neck which is destroyed 15 upon the breaking of the lug, a stopper having a chamber adapted to coincide with that of the lug when the bottle is closed, and a spring-pressed inwardly-impelled bolt contained in the lug-chamber and forced into the 20 stopper-chamber when the two are in register.

In witness whereof I have hereunto set my hand.

WILLIAM E. SWETT.
